UNITED STATES PATENT OFFICE

ABNER L. MADSEN, JR., OF CHICAGO, ILLINOIS, ASSIGNOR OF ONE-HALF TO ROBERT G. SEELEHOFF, OF CHICAGO, ILLINOIS

HANGER

Application filed September 10, 1928. Serial No. 304,902.

My invention relates to hangers of the type used for the suspension of pictures, ornaments, and the like upon a wall, and my main object is to combine a hanger of this kind with a novel ornamental mounting which may enhance the appearance of the picture or other article suspended.

A further object of the invention is to associate with the hanger an ornamental tassel unit which conceals the hanger and provides a fancy headpiece for the article suspended from the hanger.

A still further object of the invention is to utilize the novelty in the form of a stamped metallic ornament, and construct the hanger as a supplement thereof.

Another object of the invention is to incorporate in the combination of the ornament and the hanger a simple reinforcing clamp.

A final, but nevertheless important object of the invention is to construct the novel appliance from one piece of stamped sheet metal, making its production very inexpensive.

With the above objects in view and any others that may suggest themselves from the specification and claims to follow, a better understanding of the invention may be had by reference to the accompanying drawing in which—

Figure 1 is a perspective view of the novel appliance showing in part the cord which suspends the picture, wall ornament, or the like, such articles however not being shown;

Fig. 2 is a side elevation of the appliance, showing the same mounted on a wall molding;

Fig. 3 is a rear view of the upper portion of the appliance; and

Fig. 4 is a sectional detail, taken on the line 4—4 of Figure 1.

Referring specifically to the drawing, 10 denotes the fundamental feature of my invention, which is essentially a picture hook, applicable to a wall molding 11 as shown in Figure 2 and serving to support a cord 12, wire or chain for the suspension of the picture, wall ornament or other object.

In the novel embodiment I extend the picture hook section 10 upwardly, as indicated at

13, to approximately the height of the picture hook section, then bending it down and widening it to form an escutcheon or rosette 14. The rosette is extended downwardly to form the rope 15, knot 16 and cord group 17 of a typical tassel ornament. In order that the parts may remain in proper form and not be distorted by the weight of the picture or other object, I extend tongues 18 rearwardly from the side edges of the extension 13, these tongues embracing the picture hook section 10 to firmly clamp the same to the extension.

I have found that a tassel ornament on the lines suggested forms an attractive mounting over a picture or like wall display, and it has been my intention to combine such ornament with the picture hook in a way that the often unsightly appearance of the latter may be eliminated by concealing the hook entirely; also, I have thought it of advantage to build the tassel ornament and the hook as a unit. Since the standard rosette and tassel ornament of wool or other fabric is comparatively expensive and does not readily lend itself to my plans as outlined above, I have considered it of advantage to employ a metallic structure, stamped and coated ornamental to simulate the appearance of the standard article. As indicated in Figure 4, the sheet metal is pressed with a generally concavo-convex cross section, so that it stands out in relief from the wall. As indicated, the cord group 17 is made with a floor 19, pressed with many eruptive details to suggest the ends of the cords as one looks up at the ornament.

The continuation of the picture hook from the frontal ornament is along the same lines, except that the sections 13 and 10 are especially reinforced by a longitudinal corrugation or crown 20. While the top of the picture hook section may actually be higher than the rosette section 14, it will be obvious that one looking from below would not notice this, and to all intents and purposes the picture hook section will be entirely concealed.

It will be seen that my improvement, while using a standard mechanical support for the picture or other object fully conceals the same by the frontal ornament, so that the latter is the only effect apparent to the

observer. Thus, the support is firm and dependable, yet it is entirely merged in the ornamental mounting which impresses the observer, there being no suggestion whatever of the mechanical feature by the latter. At the same time, I am able to produce an appliance of this kind economically by a system of stamping and standardized ornamentation.

10 The one-piece construction of the combined ornament and hanger is of peculiar value, since it dispenses with the necessity of assembling or suiting the ornament to various styles of picture hooks. It is quite possible to press the appliance in more or less extended form and then bend the extension 13 down from the rosette 14, and finally close the clamping tongues 18. The exact method of construction is not of prime importance, since several methods may be used to produce the device whereby to assume the final form shown.

I claim:—

- 25 1. A picture hanger comprising a main hook section, a receptacle section at the bottom of the latter, an ornamental frontal section upwardly extended from the receptacle section, and means to clamp the frontal section to the hook section.
- 30 2. A picture hanger comprising a main hook section, a receptacle section at the bottom of the latter, an ornamental frontal section upwardly extended from the receptacle section, and jaws extended from the frontal section to clamp the hook section to the same.

In testimony whereof I affix my signature.
